IDENTIFICATION TAG

Wayne C. Krause, Oakland, Iowa

Application May 16, 1957, Serial No. 659,508

2 Claims. (Cl. 40—1.5)

2

the card and window are readily inserted into the circular flange 18, they are not readily removed therefrom because of the retaining action of the bead 19.

Suitable means are also provided for attaching the tag 5 to any desired garment or product. This means includes a rivet type fastener having an enlarged head 27 and a pair of deformable ends 28. The fastener is extended through a central opening 29 in a protective washer 30 which cooperates with the concave surface 14 of the 10 main body portion to clamp the garment or product 31 therebetween. The ends 28 of the fastener are then extended through the central opening 16 in the wall 12 and bent outwardly, as shown in Figure 2, to secure the parts in place. Of course, the fastening means are assembled with the device prior to inserting the identifying card 21 and transparent window 24 within the front side of the main body portion.

The circular flange 18 is also provided with a ring 32 through which a flexible chain 33 may be extended so 20 that the tag may be secured to an object independently of the rivet type fastener, if desired.

While various changes may be made in the detail construction, it shall be understood that such changes shall be within the spirit and scope of the present invention 25 as defined by the appended claims.

What I claim as new and desire to protect by Letters Patent of the United States is:

1. An identification tag comprising, in combination, 30 a main body portion having a segmental spherical wall, a flat circular flexible card having a surface for inserting identifying indicia thereon, a flat circular transparent window, means for securing said card and window in assembly with said main body portion in said flat condition, and means for fastening said main body portion 35 to an article, said segmental spherical wall having a convex surface on one side and a concave surface on the opposite side, a circular flange integral with the periphery of said wall extending outwardly in the direction toward said convex surface, and said securing means comprising 40 a beaded edge integral with the outer edge of said flange extending radially inwardly therefrom in overlapping relationship with the marginal edges of said flat flexible card and flat transparent window.

2. The combination according to claim 1, wherein said 45 fastening means comprises a washer adjacent said concave surface of said wall for receiving a section of the garment therebetween, and a rivet extending through said washer and said wall for securing said washer and main body portion together.
